FOREIGN PATENT DOCUMENTS

JP D1503285 7/2014

Primary Examiner — Paula Greene(74) *Attorney, Agent, or Firm* — Panasonic IP Management; Kerry S. Culpepper(57) **CLAIM**

We claim the ornamental design for a headphone, as shown and described.

DESCRIPTION

FIG. 1 is a top perspective view of a headphone of the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of headphone is included for the purpose of illustrating environment and forms no part of the claimed design.

1 Claim, 7 Drawing Sheets(56)
